UNITED STATES PATENT OFFICE.

JOSEPH LOEB, OF PHILADELPHIA, PENNSYLVANIA.

DESIGN FOR FRINGE.

SPECIFICATION forming part of Design No. 21,661, dated June 28, 1892.

Application filed May 28, 1892. Serial No. 434,797. Term of patent 3½ years.

To all whom it may concern:

Be it known that I, JOSEPH LOEB, a citizen of the United States, residing in the city and county of Philadelphia, State of Pennsylvania, have invented and produced a new and original Design for a Fringe, of which the following is a specification, reference being had to the accompanying drawing, forming part thereof.

10 The leading feature of my design for a fringe is tabs with pendants thereon, forming a zigzag edge.

In the drawing, A designates tabs on the head B of the fringe, said tabs being alternately long and short and having on the lower 15 end of each a pendant C, forming a zigzag edge.

I claim—

The design for a fringe, substantially as shown and described.

JOSEPH LOEB.
